CAR DOOR

Filed April 24, 1926

FIG. 3 *GEORGE BINET DOREY*

By N. Now His wife

UNITED STATES PATENT OFFICE

GEORGE BINET DOREY, OF EVANSTON, ILLINOIS, ASSIGNOR TO ENTERPRISE RAILWAY EQUIPMENT COMPANY, OF CHICAGO, ILLINOIS, A CORPORATION OF ILLINOIS

CAR DOOR

Application filed April 24, 1926. Serial No. 104,426.

My invention relates to improvements in car doors.

My invention relates to doors such as are usually employed in freight cars and the like and relates more particularly to an improved reinforced metal door. In cars of the freight car type the doors are usually supported at either the top or bottom and mounted to have sliding movement across a door opening, the doors being maintained against outward movement by suitable guides disposed at the upper and lower margins thereof. There being a considerable distance between the said upper and lower supports there is a tendency for the door to sag and buckle vertically and also to warp on diagonal lines. Various expedients have been suggested to overcome such defects, such as forming the vertical margins of stronger and heavier sections and placing additional horizontal cross members from one vertical margin to the other but such construction calls for greatly added weight which renders the door excessively heavy and expensive.

It is an object of my invention to provide a construction for a freight car door which will strengthen the same against warping and buckling and still be light in weight and relatively cheap.

It is also a further object of my invention to provide a door construction which will permit of reinforcement by rigidifying embossments defining intelligible indicatory symbols, whereby the door will not only possess strength but also have advertising value.

A still further object of my invention is to provide a freight car door having the body formed mainly of metal sections of different thicknesses and to provide additional reinforcing members having considerable body whereby the strength of the thicker sections of the door will operate to brace and strengthen the sheets formed of thinner material.

Other objects of the invention will more clearly appear from the description herein-after following.

In the drawings forming a part of this specification, Fig. 1 is a front elevational view of a freight car door embodying my improve-

ments. Fig. 2 is a vertical sectional view taken through the door and on a line corresponding substantially to a line 2—2 of Fig. 1. Fig. 3 is an enlarged horizontal sectional view corresponding substantially to a line 3—3 of Fig. 1, intermediate parts being broken away to better accommodate the view on the sheet. In this figure various details of the car construction adjacent the door are illustrated. Fig. 4 is a sectional view illustrating the lower portion of the door in relation to the supporting structure when such support is disposed at the bottom of the door instead of at the top thereof.

In said drawings, the usual front and rear door posts defining the door opening of a box car are illustrated at 10 and 11 respectively, and the threshold of the door opening is indicated at 12. The improved door is indicated generally by the reference character A. As shown, the door includes a marginal rectangular frame which includes a top horizontal member 13, and front and rear vertical marginal members as indicated at 14 and 15 respectively. The said marginal members 13, 14 and 15 are preferably formed of Z-shaped rolled sections with flanges 16, 17 and 18 of the respective marginal members disposed in the front plane of the door and the intermediate webs of the respective members project inwardly of the front plane of the door and are disposed substantially at right angles thereto. The respective vertical marginal members 14 and 15 are braced to the top member 13 by gussets 19—19. The body of the door intermediate the said frame members is preferably formed of two sheet metal panels as indicated at 20 and 21. These panels are preferably overlappingly united to each other along a horizontal line of rivets as indicated at 22, said joint being disposed at an appreciable distance above the lower margin of the door. The edges of the respective panels 20—21 are secured flatwise to the inwardly projecting flanges 16, 17 and 18 of the respective marginal members 13, 14 and 15.

The lower margin of the door is rigidified by bending the lower portion of the lower panel 21 inwardly as indicated at 23 and

thence downwardly, thereby presenting a depending flange 24 disposed at an appreciable distance from the front plane of the door. The lower panel 21, which is preferably made of thicker material than the upper panel 20, thus serves as a strong member for the lower portion of the door, and serves to maintain the frame against racking and also protects the lower part of the door against injury, due to shifting loads in the car. Secured to said depending flange 24 of the lower panel 21 on the inner side of the door is a flat plate 25 which extends upwardly above the lower margin of the door for an appreciable distance, and provides a smooth and even surface for contacting with the car structure 12 at the lower portion of the door opening as the door is moved. Interposed between said plate 25 and the paneling of the door is a wooden beam member 26 which also acts as a filler member, and operates to strengthen the door against bending and warping. This arrangement in conjunction with the strong lower panel 21 provides an exceedingly strong construction at the lower margin of the door. Extending upwardly and outwardly from the central portion of the beam member 26 are braces 27-27, which together form a V-shaped reinforcement extending upwardly for preferably more than half the vertical height of the door. The said braces 27-27 being extended outwardly to meet the vertical marginal reinforcements co-operate with the same to resist bending of the door on vertical lines. Braces 27-27 are preferably formed of wooden beams united by soft rivets 28 to the heavy lower panel 21 and also to the relatively thinner panel 20, and in this manner a portion of the strength of the lower heavy plate is communicated to the weaker upper plate.

The upper panel 20 is rigidified by having integral embossments pressed therein, said embossments being preferably in the form of intelligible indicator characters or symbols 29. The embossment is preferably formed of a size to rigidify the unsupported portion of the plate and in the present design embodied in this invention it will be seen that the diamond shape 30 extends between the respective vertical marginal beams 14 and 15 while the circular portion 31 extends tangent to the V arranged bracing structure formed by braces 27-27. The unsupported portion of the plate is thus rigidified by an embossment combining strength and utility and bending of the door intermediate said embossments and the marginal frame will be further prevented by the diagonally extending braces 27-27 which transmit such bending strains to the respective margins of the door. This arrangement permits the use of thin material for the upper panel 20 thereby saving weight and securing sharper definition for the characters of the embossed sym-

bol. The use of wood for diagonal beams 27-27 and lower horizontal beam 26 provides the necessary body to counteract the warping tendency of the door.

In Fig. 1 the door is shown as provided with brackets 32 and rollers 33 whereby the door is adapted to be suspended from a rail adjacent the top of the door but such construction is optional as the door may be carried on rollers 34 mounted on brackets 35 carried by the car structure as illustrated in Fig. 4. When the door is supported at the top margin, the lower depending flange 24 co-operates with suitable guides to prevent outward movement of the door and when the door is supported at the bottom, as shown in Fig. 4, the door is maintained against outward movement by suitable guiding means acting on the upstanding flange 36 of the top horizontal member 16.

While I have shown and described a specific embodiment of my invention, the same is merely illustrative and I contemplate all modifications within the scope of the appended claim.

What I claim is:

A sliding door for railway cars including a metallic body portion defining the main body of the door and inwardly extending marginal wall portions angularly related with respect to the main body portion and cooperating therewith to provide a box shaped structure, said main body portion having rigidifying means embossed therein and extending outwardly of the box shaped section, said rigidifying means being adapted to provide reinforcement horizontally across the door, said reinforcement terminating short of the vertical marginal sections of the box shape; and supplementary reinforcement for the inner side of the door disposed in the box shape portion of the door, said last named reinforcements extending diagonally across the corners of the door and adapted to bridge as beams the space intermediate the embossed rigidifying means and the marginal sections to thereby provide with said rigidifying means continuity of reinforcement intermediate the vertical marginal sections.

In witness that I claim the foregoing I have hereunto subscribed my name this 21st day of April, 1926.

GEORGE BINET DOREY.
